UNITED STATES PATENT OFFICE.

DOMINICK P. MAMMELLI, OF NEW ORLEANS, LOUISIANA.

WINDOW-LATCH.

1,185,422.

Specification of Letters Patent. Patented May 30, 1916.

Application filed January 17, 1916. Serial No. 72,523.

To all whom it may concern:

Be it known that I, DOMINICK P. MAMMELLI, a citizen of the United States, residing at New Orleans, in the parish of Orleans and State of Louisiana, have invented new and useful Improvements in Window-Latches, of which the following is a specification.

This invention relates to window latches, and it has specific reference to a latch for securely locking the lower sash of a window in position with respect to the window frame.

The invention has for its object to produce a simple and effective latch of improved construction whereby the bottom sash when lowered to its closed position will be effectively secured until released by means provided for the purpose.

20 A further object of the invention is to produce a device of the class described in which the latch may be released to permit a window to be opened by means of a push button, avoiding the use of keys or the like.

25 With these and other ends in view which will readily appear as the nature of the invention is better understood, the same consists in the improved construction and novel arrangement and combination of parts 30 which will be hereinafter fully described and particularly pointed out in the claims.

In the accompanying drawing has been illustrated a simple and preferred form of the invention, it being, however, understood 35 that no limitation is necessarily made to the precise structural details therein exhibited, but that changes, alterations and modifications within the scope of the claims may be resorted to when desired.

40 In the drawing, Figure 1 is a perspective view showing the sill and the lower portion of a window frame, together with a portion of the bottom sash, the same having the invention applied thereto. Fig. 2 is a vertical sectional view taken substantially on the line 2-2 in Fig. 1. Fig. 3 is a vertical sectional view similar to Fig. 2, but enlarged, and showing the bottom sash in locked position. Fig. 4 is a perspective 45 detail view of the latch casing. Fig. 5 is a perspective detail view of a pivoted latch member. Fig. 6 is a perspective detail view showing the latch engaging catch member which is to be mounted on the bottom rail 50 of the bottom sash.

Corresponding parts in the several figures are denoted by like characters of reference.

The sill 15 of the window to which the device is to be applied is provided with a mortise or recess in which the casing or 60 housing 16 of the improved device is mounted, said casing having at its upper edge a flange 17 which is apertured for the passage of fastening members, such as ordinary wood screws 18, the heads of which are preferably countersunk in the flange.

The housing includes wall members which for convenience will be designated as the front and rear wall members 19, 20. The rear wall member 20 is provided on the 70 inner face thereof near the upper edge of the housing with bearing sleeves 21 for the reception of a pin or pivot member 22 on which is hingedly supported a latch member 75 consisting of a plate 23 having at the upper end thereof a bearing sleeve 24 and a beveled head portion 25 having a shoulder 26. A spring 27 interposed between the plate 23 and the rear wall of the housing serves to force the lower end of the latch member 80 in a forward direction toward the front wall of the housing. The said front wall is provided near the lower edge thereof with an aperture 27' for the reception of a 85 nipple 28 projecting at one end of a cylindrical socket 29 which by means of the said nipple is connected with the front wall of the housing, as clearly seen in Figs. 2 and 3, the nipple being preferably externally threaded to enable it to be conveniently assembled with the housing, the aperture 27' of which is correspondingly threaded.

Extending through the nipple 28 and the socket member 29 is a rod 30 having at one 95 end a head 31 which is positioned within the housing 16 in such fashion as to abut on the lower end portion of the latch plate 23. Coiled about the rod 30 within the housing 29 is a spring 32 which is tensioned by means of a disk or washer 33 which is in threaded engagement with the rod 30, the outer or forward end of which is screw threaded, as shown. The tension of the spring 32 is exerted against the washer 33 100 to force the rod in a forward or outward direction through a horizontal aperture 34 in the sill 15. A push button 35 is placed in threaded engagement with that portion 105 of the rod which extends beyond the inner 110

face of the sill, and an escutcheon plate 36 is mounted on the sill surrounding the push button.

Secured on the under face of the bottom rail 37 of the bottom sash 38 is a catch member consisting of a plate 39 having a flange 40 provided with apertures 41 for the passage of fastening members, such as ordinary screws. At its lower end the plate 39 has a catch hook 42 adapted to engage with the beveled head 25 of the latch member 23 to secure the bottom sash in locked position, the parts being properly proportioned so that when the bottom sash is forcibly moved down to engage the sill, the catch member 39 will enter the housing 16, causing the catch hook 42 to engage beneath the shoulder 26 of the beveled head 25 of the spring projected latch member. In order that the catch member 39 may readily engage and enter into the housing 16 the said catch member is downwardly beveled, as shown. Thus, if the catch member should be slightly out of alinement with the housing, it will still enter the same and be guided safely within the housing without danger of injury or breakage of any of the parts.

In order to release the latch so as to permit the bottom sash to be opened it is only necessary to manipulate the push button 35, whereby the rod 30 will be pushed in a rearward or inward direction, causing the head 31 to engage the spring projected latch plate 23, forcing the latter against the tension of the spring 27 in the direction of the rear wall of the housing and disengaging the shoulder 26 from the hook 42.

It will be seen that I have produced a very simple and effective window latch which by reason of its construction as herein set forth may be easily and inexpensively installed on any window casing of ordinary construction.

Having thus described the invention, what is claimed as new, is:—

1. In a latch of the character described, a housing open at its upper end and provided with an attaching flange at its upper edge, the rear wall of said housing having bearing sleeves on its inner face at the upper edge thereof, a latch member consisting of a plate having at its upper end a beveled head and at its upper edge a bearing sleeve, a pin engaging the bearing sleeves on the rear and at the upper edge of the latch plate, and a spring interposed between the lower portion of the latch plate and the rear wall of the housing.

2. In a latch of the character described, a housing open at its upper end and provided with an attaching flange at its upper edge, the rear wall of said housing having bearing sleeves on its inner face at the upper edge thereof, a latch member consisting of a plate having at its upper end a beveled head and at its upper edge a bearing sleeve, a pin engaging the bearing sleeves on the rear and at the upper edge of the latch plate, and a spring interposed between the lower portion of the latch plate and the rear wall of the housing, the forward wall of the housing being provided with an aperture near its lower edge; in combination with a cylindrical socket member having a nipple engaging the aperture, a headed bolt extending through the nipple and the socket member with its head adjacent to the spring actuated latch plate, a spring coiled about the bolt within the socket, a spring tensioning washer threaded upon the bolt, and a push button mounted on the outer end of said bolt.

3. In a latch of the character described, a housing open at its upper end and provided with an attaching flange at its upper edge, the rear wall of said housing having bearing sleeves on its inner face at the upper edge thereof, a latch member consisting of a plate having at its upper end a beveled head and at its upper edge a bearing sleeve, a pin engaging the bearing sleeves on the rear and at the upper edge of the latch plate, and a spring interposed between the lower portion of the latch plate and the rear wall of the housing, the forward wall of the housing being provided with an aperture near its lower edge; in combination with a cylindrical socket member having a nipple engaging the aperture, a headed bolt extending through the nipple and the socket member with its head adjacent to the spring actuated latch plate, a spring coiled about the bolt within the socket, a spring tensioning washer threaded upon the bolt, and a push button mounted on the outer end of said bolt.

In testimony whereof I affix my signature in presence of two witnesses.

DOMINICK P. MAMMELLI.
